UNITED STATES PATENT OFFICE.

JACOB HECKENLIVELY, OF EUREKA, KANSAS.

MOTOR.

SPECIFICATION forming part of Letters Patent No. 297,394, dated April 22, 1884.

Application filed January 30, 1884. (No model.)

To all whom it may concern:

Be it known that I, JACOB HECKENLIVELY, of Eureka, in the county of Greenwood and State of Kansas, have invented a new and Improved Motor, of which the following is a full, clear, and exact description.

The object of my invention is to provide a simple, durable, inexpensive, and practical motor for driving pumps, saws, and other machinery.

The invention consists of a contrivance of a drum from which is suspended, by a cord or chain, a weight, which descends by its gravity to unwind the cord or chain and give motion to a train of gears, which drive a shaft carrying a cam-wheel, with which a machine may directly be connected by a pitman, a suitable governor device being provided to press a brake-lever against the cam-wheel to control the speed of the motor and connected machinery, all as hereinafter fully described and claimed.

Reference is to be had to the accompanying drawings, forming part of this specification, in which similar letters of reference indicate corresponding parts in both the figures.

Figure 1 is a side elevation of my improved motor, with the pitman-guide in section; and Fig. 2 is a plan view of the same.

To any suitable frame or base, *a*, I fix bearings *b b*, *c c*, and *d d*, in which are journaled, respectively, the shafts *e f g*. A drum, *h*, is mounted rigidly on shaft *e*, and around the drum a rope or chain, *i*, is wound, which carries at one end the weight *j*. The drum *h* has fixed to it the ratchet-wheel *k*, with which a pawl, *l*, pivoted to a large gear-wheel, *m*, may be thrown into gear, to cause wheel *m*, which is mounted loosely on shaft *e*, to be revolved by the unwinding of drum *h* by the uncoiling of its rope or chain *i* by the gravity of the descending weight *j*. This arrangement permits shaft *e* to be turned backward by its hand-crank *e'*, to coil the rope on the drum without effect on wheel *m* or its connected gearing; and as the rope *i* unwinds, the pawl engages the ratchet to drive wheel *m*, as will readily be understood. The gear-wheel *m* meshes with a pinion, *n*, fast on shaft *f*, to which pinion *n* or shaft *f* is fixed a large gear-

wheel, *o*, which in turn meshes with a pinion, *p*, fast on the shaft *g*, which is the driving-shaft of the motor, and transmits the power to a pump, *q*, or other machinery to be driven.

The letter *r* indicates a cam-wheel having a zigzag or star-shaped cam-groove, *s*, therein, in which the pin or anti-friction roller *t* on the end of the pitman *u* engages for reciprocating the pump piston or plunger, the pitman being suitably guided in ways *v*, fixed to the base or frame of the machine. The cam-groove may be arranged in one or more convolutions to cause one or more strokes of the pitman for each revolution of shaft *g* and wheel *r*, according to the required speed of the machine to be driven. In the example shown the cam-groove is shaped to give six strokes of the pitman to one revolution of the driving-shaft. The pitman may be guided to work horizontally as well as vertically, or at any desired inclination, as circumstances may require for any special work to be done.

For a governor device, to automatically control the speed of the motor and machinery driven thereby within safe limits, I fix on shaft *g* the pulley *w*, around which a belt, *x*, passes to a pulley, *y*, on a vertical shaft, *z*, which has a long bearing, for steadiness, in the base *a*, and carries fixedly a large grooved wheel, *a'*, from which a belt, *b'*, passes around a grooved pulley, *c'*, on the upright shaft *d'*, which carries the toggle-jointed and weighted arms of an ordinary ball-governor, *f'*, the sleeve *g'* of which is connected to the end of a brake-lever, *h'*, which passes along beneath the periphery of cam-wheel *r*, the lever *h'* being curved in about the same radius as the edge of the wheel, and then pivoted at *i'* to a standard rising from base *a*, or to the base itself. With the parts thus arranged, when the speed becomes excessive, the governor-sleeve *g'* will be raised, which will carry the brake-lever *h'* against the cam-wheel *r* and check the speed, as required.

If desired, the driving-shaft *g* may be extended at or from the end opposite the cam-wheel, and pulleys be fitted to it for connection by driving-belts to distant machinery.

The speed of the driving-shaft may be varied or multiplied by changing the size and num-

ber of gears in the wheel-train connecting it with the drum h , and its cord or chain i and weight j .

My improved motor is simple, durable, and easily managed, and is adapted for connection with many classes of machinery, giving it a wide range of usefulness.

Having thus described my invention, what I claim as new, and desire to secure by Letters

10 Patent, is—

1. A motor constructed with a drum and a weight suspended therefrom, said drum connecting by a ratchet-and-pawl device with a gear-train, which drives a shaft carrying a 15 wheel having a zigzag or star-shaped cam-groove, for driving the pitman of a pump or

other machine, and the said driving-shaft connecting by a ball-governor with a pivoted brake-lever acting on the periphery of the cam-wheel to control the speed, substantially as shown and described.

2. The combination, with the sleeve g' of the ball-governor f' and the cam-wheel r , of the pivoted brake-lever h' , connected to be lifted by the sleeve against the cam-wheel when the speed is excessive, substantially as shown and described.

JACOB HECKENLIVELY.
